UNITED STATES PATENT OFFICE

2,535,136.

COLLAPSIBLE HAT HOLDER

Morris Jacobson, Chicago, Ill., assignor to Arvey Corporation, Chicago, Ill., a corporation of Illinois

Application November 19, 1945, Serial No. 629,654

1 Claim. (Cl. 211—32)

1

This invention relates to improvements in hat holders, and is more particularly concerned with the provision of a collapsible hat holder comprising a plurality of back sections hingedly connected in end-to-end relation and having hat receiving members pivotally mounted thereon for gravitational movement against the front face of their respective back sections, said back section and hat receiving members being preferably formed of flat material, such as cardboard, and adapted to be folded and arranged in a compact stacked relation for shipping or storage.

It is a further object of this invention to provide a collapsible hat holder in which the hat receiving members are formed with apertures to receive the bowl of a hat with the brim thereof engaged between the inner side of the hat receiving member and the front face of a back section.

It is a further object of this invention to provide a collapsible hat holder embodying back sections and hat receiving members which may be inexpensively formed from sheet material and readily assembled by means of connecting links formed of wire or string to provide a hat holder of the size desired for holding a predetermined number of hats.

Hat holders of the type hereinafter described are suitable for use in hat stores, display windows, check rooms, restaurants, and other places where it is desirable to arrange a plurality of hats along a wall. When the hat holder is not in use, it may readily be folded into a small compact unit suitable for storage.

This invention embodies other novel features, details of construction and arrangement of parts which are hereinafter set forth in the specification and claim and illustrated in the accompanying drawing wherein:

Fig. 1 is a front elevational view showing a collapsible hat holder embodying features of this invention.

Fig. 2 is a side elevational view of same.

Fig. 3 is an enlarged fragmentary side elevational view illustrating the manner in which hats are mounted upon the hat holder.

Fig. 4 is a side elevational view showing the manner in which the several hat sections may be superimposed, one upon the other, in stacked relation to form a compact unit for shipping or storage.

Referring now to the drawings for a better understanding of this invention, the hat holder is shown as comprising a plurality of back sections 6 which are hingedly connected in end-to-end re-

2

lation by means of connecting links 7 formed of string, wire, or other suitable material. At one end of the hat holder is provided a hanger section 8 which is connected to the upper back section 6 by means of connecting links 7 and formed with an aperture 9 to receive a mounting hook (not shown) for mounting the hat holder upon the side of a wall.

A hat receiving member 11 is pivotally mounted on each set of rings 7 for movement relative to the front face of its respective back section 6, and is provided with an aperture 12 to receive the bowl 13 of a hat 14.

A hat is mounted on the hat holder by first pivoting a hat receiving member 11 upwardly away from the face of its respective back section 6 in order to insert the bowl 13 of a hat into the aperture 12 with the brim portion 15 disposed against the back face of the member 11. After a hat is thus mounted, the member 11 is maintained in position by gravity against the front face of its back section 6 with the brim portion 15 interposed therebetween.

In the construction of a hat holder of the type thus described, it will be noted that the back sections 6 and hat receiving members 11 may be inexpensively formed from cardboard or other sheet material and suitably connected to form an articulated construction adapted to be folded in the manner illustrated in Fig. 4 to form a compact unit suitable for shipping or storage.

Collapsible hat holders of the type described are particularly useful in restaurants, check rooms, and the like, as hats may readily be mounted or removed from the hat holder by merely pivoting a hat receiving member 11 upwardly.

While this invention has been shown in but one form, it is obvious to those skilled in the art that it is not so limited but is susceptible of various changes and modifications without departing from the spirit and scope of the claimed invention.

I claim as my invention:

45 In a collapsible hat holder adapted to be suspended in a vertical plane, a plurality of similar back sections in the form of flat blanks of cardboard of greater length than width arranged end-to-end, each back section being formed adjacent each end thereof with a pair of apertures, each back section being pivotally connected to its adjacent back section for movement through an arc of approximately 360° by means of rings disposed in said apertures, a plurality of similar hat receiving members in the form of flat blanks of

cardboard, one end of each hat receiving member being formed with a pair of apertures to receive a pair of said rings whereby said member may be suspended for pivotal movement along a single axis toward and away from the face of its respective back section, said hat receiving members and back sections being substantially coextensive in length, the width of said hat receiving members being greater than the width of said back sections, each hat receiving member being formed with an opening to receive the bowl of a hat, and a hanger section pivotally connected to one of said back sections.

MORRIS JACOBSON.
